UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 13,338, dated October 17, 1882.

Application filed September 21, 1882. Term of patent 3½ years.

To all whom it may concern:

Be it known that I, ARTHUR L. HALLIDAY, of New York, in the county of New York and State of New York, have invented a new and original Design for Carpets, of which the following is a specification.

This invention relates to a new and original design for carpets and similar fabrics; and it consists in the novel grouping and configuration of parts hereinafter more fully described.

The accompanying photograph illustrates a face view of a carpet having my new design.

A is a flower group containing a bunch of circular flowers, b, surrounded by leaves c, and inclosed within an irregular frame composed of a series of squares, a, set alongside or upon each other.

B is a group composed of a vine like figure, which bears star-flowers h, leaves l, circular flowers e and d, and bud-like flowers f. This vine B is inclosed by a series of the squares a, which come near together at the central portion of the vine and leave larger open spaces at each end thereof.

D is a branch bearing flowers g and leafy branches i, and is also inclosed in a frame composed of the square figures a.

The whole effect of the design is that of openings or frames formed by the closely-set

squares a, in which openings appear the flower 30 and vine figures described.

I claim—

1. The design for carpets, consisting of the group A, containing figures a b c, substantially as shown.

2. The design for carpets, consisting of the figures b and c, substantially as shown.

3. The design for carpets, consisting of the vine B, containing figures h l f e d, substantially as shown.

4. The design for carpets, consisting of the vine B, surrounded by figures a, substantially as shown.

5. The design for carpets, consisting of the group D, containing figures g i, substantially as shown.

6. The design for carpets, consisting of the group D, containing figures g and i and surrounded by figures a, substantially as shown.

7. The design for carpets, consisting of the group A, containing figures a b c, vine B, containing figures h l f e d, group D, containing figures d and i, and figures a, substantially as shown.

ARTHUR L. HALLIDAY.
